UNITED STATES PATENT OFFICE.

ROBERT W. DONLEY, OF PHILADELPHIA, PENNSYLVANIA.

SPINDLE.

Application filed January 19, 1924. Serial No. 687,317.

To all whom it may concern:

Be it known that I, ROBERT W. DONLEY, a citizen of the United States, residing at Philadelphia, in the county of Philadelphia and State of Pennsylvania, have invented 5 new and useful Improvements in Spindles, of which the following is a specification.

This invention relates to improvements in thread holding devices for use in cotton 10 or textile mills, the general object of the invention being to provide improved means for supporting the thread holder so that it can rotate with the least amount of friction.

Another object of the invention is to 15 provide means for easily and quickly detaching the holder from its support.

This invention also consists in certain other features of construction and in the combination and arrangement of the several parts, to be hereinafter fully described, 20 illustrated in the accompanying drawing and specifically pointed out in the appended claim.

In describing my invention in detail, reference will be had to the accompanying 25 drawing wherein like characters denote like or corresponding parts throughout the several views, and in which:—

Figure 1 is an elevation of the improvement.

Figure 2 is a longitudinal sectional view.

Figure 3 is a section on line 3—3 of Figure 2.

Figure 4 is a section on line 4—4 of Figure 2.

In these views, 1 indicates a part of the main platform of the machine to which the attachment is applied and 2 indicates the supporting member which passes through a 40 hole in the platform and is threaded to receive the base 3 and the nut 4 which clamps the support to the platform. A passage 5 extends longitudinally through the support and a grease cup 6 is threaded to the lower 45 end of the support so that when the cup is turned the grease therein will be forced through the passage 5. The upper end of the support is formed with a recess 7 to form a seat for a ball 8. The thread holder 50 A consists of the spindle 9 and a hollow pulley member 10 which receives the upper

end of the supporting member and rests upon the ball 8 so that the member A is rotatably supported. It has an annular groove 11 adjacent its lower end which is 55 engaged by a latch member 12 carried by the spring strip 13 which is fastened to the base 3, the latch member being provided with a handle 14 so that it can be pulled from the groove when the member A is to 60 be removed.

From the foregoing, it will be seen that the holder A is supported so that it can rotate with practically no friction and lubricant can be supplied to the parts by 65 tightening the cup 6 to force the lubricant through the passage 5 to the ball seat. The holder can be easily removed from the support by pulling the latch member outwardly by its handle. The spring strip 13 acts to 70 hold the latch member in engagement with the groove. The part 10 acts as a pulley for receiving the driving belt.

It is thought from the foregoing description that the advantages and novel features 75 of my invention will be readily apparent.

I desire it to be understood that I may make changes in the construction and in the combination and arrangement of the several parts, provided that such changes so fall within the scope of the appended claim.

What I claim is:—

A device of the class described comprising a tubular support having a ball seat at 85 its upper end and a threaded lower end, a nut engaging the screw threads for attaching the support to a platform, a grease cup threaded to the lower end of the support and adapted to force lubricant through the 90 support to the ball seat, a ball in the seat, a holder having a socketed pulley member at its lower end for receiving the upper part of the support so that the holder will rest upon the ball, said pulley member having an annular groove adjacent its lower 95 end and a latch member connected with a part on the support and engaging the groove.

In testimony whereof I affix my signature.

ROBERT W. DONLEY.
